UNITED STATES PATENT OFFICE.

THOMAS M. PLATTS, OF NEWARK, NEW JERSEY.

PUNCHING-MACHINE.

SPECIFICATION forming part of Letters Patent No. 314,474, dated March 24, 1885.

Application filed April 11, 1884. (No model.)

To all whom it may concern:

Be it known that I, THOMAS M. PLATTS, a citizen of the United States, residing at Newark, in the county of Essex and State of New Jersey, have invented certain new and useful Improvements in Strap-Punching Machines; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention relates to that class of punching-machines for perforating leather straps, &c., having the hollow punch arranged upon a reciprocating bar and operating in connection with a presser-foot and feed, the object of the invention being to facilitate and perfect the operation of punching or perforating.

The invention consists in the arrangements and combinations of parts, substantially as will be hereinafter set forth, and finally embodied in the clauses of the claim.

Referring to the accompanying drawings, comprised in four sheets, in which like letters and figures of reference indicate corresponding parts in each of the several figures, Figure 1 is a side elevation of the machine, showing the relation of the several parts thereof. Fig. 2 is an end view showing especially the punch, presser-foot, and feed. Fig. 3 is a plan of the table or bed-plate, a section of the arm of the machine being taken through line x , Fig. 1. Fig. 4 is a detail illustrating a portion of the feed-driving mechanism. Fig. 5 illustrates a ratchet-and-pawl attachment of said driving mechanism, and Fig. 6 is a sectional view of a punch-bearing adapted to be changed in position.

In said drawings A is a bed-plate having preferably three legs, $a a a$, adapted to be secured upon a bench, B. These raise the said plate considerably above said bench to allow for certain feeding mechanism. Upon said bed A is formed or secured an overhanging arm, C, which provides bearings for a horizontal punch-bar-operating shaft, D. At one end of said shaft D is arranged a driving-wheel, E, which may be actuated by a belt or by a crank-handle, b. Contiguous to the driving-wheel

upon said shaft is arranged a crank or eccentric, e, and at the opposite end thereof is arranged a crank-wheel, e. The overhanging end of the arm C furnishes bearings for the vertical shaft or bar f, said bar being actuated to a reciprocating movement by the crank e, through the medium of a crank-pin, a horizontally-sliding plate, g, connected by said pin to the crank, and a vertically-sliding portion, h, carrying the said plate g in a groove therein and sliding in a vertical slot in the arm. (Shown in Fig. 2.) The said portion h holds the reciprocating punch-bar, the latter being adjustably secured in a perforation or opening therein by a set-screw, h'. The said bar may be raised or lowered in its bearings to suit the punch-disk hereinafter mentioned.

To engage the strap on the upper side and force it into engagement with the feed-wheel, so that the latter will cause said strap to travel forward at each movement thereof, I provide a presser-foot wheel, G, adjustably secured on a vertically-sliding bar, H, sliding in bearings u u'. Said presser-foot is raised from engagement by a cam-lever, v, fulcrumed on the bar and resting on the bearing u'. Said presser-foot is held firmly against the strap by a spring, w, arranged around said bar and bearing 80 against the bearing u' and an adjustable piece, 2, secured to and moving with said bar. Said adjustable piece is provided with a flat side, which engages with the flat face of the arm C. It is thereby prevented from turning, and, being rigidly secured to the bar H, the latter and the presser-foot secured thereon are prevented from turning in and on their respective bearings. By setting the adjustable piece more or less near the bearing u' the pressure of the 90 presser-foot is varied.

Beneath the bed-plate A, working in bearings $j j^2$, the latter being preferably in the leg a', is arranged the shaft k, having at one end the crank l and at the other a slotted arm, m. (Shown more clearly in Fig. 4.) Said slotted arm is connected with the eccentric e by the connecting-rod n and straps o. The crank-pin p of the crank l carries a pawl, q, which engages a ratchet-wheel, r, (Figs. 1 and 5,) the pawl being held into engagement with the ratchet by the spring s. Said ratchet-wheel is secured upon and revolves with the feed-wheel F in the bearings t. The said feed-wheel

projects slightly above the bed-plate, and has an intermittent motion received from the ratchet and pawl attachments, as will be understood. The surface of the wheel may be roughened, as indicated in Fig. 1; but when it is desired to work on leather finished on both sides, I provide a wheel the frictional surface of which is covered with a band of rubber or other soft flexible substance suitable for the purpose.

Upon the bed-plate *A* beneath the punch is arranged a revolving disk, 3. (Shown in sectional detail in Fig. 6.) Said disk is provided with a shank, 3', and the bed-plate *A* is suitably perforated to receive said shank and a set-screw. Said set-screw engages with the shank and holds the disk in position. When the punch-bearing, (indicated in Fig. 3 by 5,) becomes worn or deeply cut, the disk may be readily readjusted by loosening the set-screw, turning the disk to a new bearing, and then again securing the parts.

To bring the strap to be perforated into proper relation to the punch, I provide adjustable guides 6 6, which are arranged on a right and left hand screw, 7, working between bearings 8 8, and provided with a finger-piece, 10, which last when turned causes the guides 6 6 to move from a center in line with the punch equally in opposite directions, so that the said guides will always stand at equal distance from said center and the center of the strap be perforated. The screw 11 bearing against the center of the finger-piece enables the screw and guides to be readily removed from their bearings, when necessary, by simply loosening the same. The crank-shaft *k* is given a rocking motion by means of an arm, *m*, projecting from the end thereof, to which arm the connecting-rod *n* is adjustably secured by means of a bolt and nut, the bolt working in a slot, 12, in said arm. The connecting-rod is given a reciprocating motion by means of the eccentric *c*, which motion is transmitted to the arm *m* and feed-shaft *k*. The crank on said shaft, operating the pawl, causes the same to move the ratchet and feed wheels intermittently, as will be understood. The connecting-rod, being adjustably secured to the arm *m*, can be moved toward or from the shaft *k*, and by this arrangement the machine is adapted to make the perforations in the strap at any desired distances apart, the distances apart of said perforations being increased by

securing the connecting-rod to the arm at a reduced distance from the rocking shaft. The arm is provided with graduation-marks 13, and the rod *n* with a gage, 14, movable therewith to enable the operator to readily adjust the machine to perforate the strap at the desired distances.

Having thus described the invention, what I claim as new is—

1. The combination, in a punching-machine, of the guides 6 6, arranged on a right-and-left screw, the bearings 8 8 of the bed-plate, a suitable finger-piece, 10, and a screw, 11, all arranged and operating substantially as and for the purposes set forth.

2. In a punching-machine, the combination of the horizontal shaft *D*, actuating the vertically-sliding piece, said vertically-sliding piece, the bar *f*, secured in said sliding piece by the set-screw *h'*, and the punch, all said parts being arranged and operating substantially as and for the purposes set forth.

3. In a punching-machine, the combination of the arm *C*, presser-foot bar *H*, bearings *u u'*, adjustable piece 2, bearing against the face of the said arm and preventing the presser-wheel from turning, the spring *w*, and said presser-wheel, all said parts being arranged and operating substantially as set forth.

4. In a punching-machine, the combination, with the rocking shaft *k*, actuating the feeding mechanism intermittently, of a slotted and graduated arm secured on one end of said shaft, a connecting-rod, a bolt and nut, and a gage moving with said rod, substantially as set forth.

5. In a punching-machine, the combination, with a bed-plate carrying a reciprocating punch, and having a series of perforations, one perforation to receive the shank of a bearing-disk, and the other a set-screw, of said reciprocating punch, said bearing-disk having a shank, and a set-screw to hold said shank in its perforation, said parts being arranged and operating substantially as and for the purposes set forth.

In testimony that I claim the foregoing I have hereunto set my hand this 28th day of February, 1884.

THOMAS M. PLATTS.
